SANDING MACHINE

Raymond A. Reid, Cedar Rapids, Iowa

Application December 27, 1937, Serial No. 181,753

15 Claims. (Cl. 51—174)

This invention relates to floor sanding devices and has particular relation to a device suitable for sanding, finishing and polishing flat surfaces such as floors and the like.

5 A general object of my invention is to provide a power driven device for sanding, scraping, polishing and otherwise conditioning and finishing floors and like flat surfaces.

Another object of my invention is to provide 10 an extremely simple and reliable device of the above character.

Still another general object of my invention is to provide, in a machine of the above character, means for causing the work-engaging member of 15 the machine to move with an eccentric or elliptical movement.

Another object of my invention is to provide, in a device of the above character, counterbalancing or counter-poise forces for minimizing vibration 20 in the machine.

Another object of my invention is to provide means for materially reducing the wear of the working parts of a device of the above character.

Another object of my invention is to provide 25 readily interchangeable work-engaging means.

Other and further features and objects of the invention will be more apparent to those skilled in the art upon a consideration of the accompanying drawings and following specifications, where- 30 in is disclosed a single exemplary embodiment of the invention, with the understanding, however, that such changes may be made therein as fall within the scope of the appended claims, without departing from the spirit of the invention.

35 In said drawings:

Figure 1 is a view in perspective of a device constructed according to one embodiment of my invention.

Figure 2 is a fragmentary view in perspective 40 of the under side of the device shown in Figure 1.

Figure 3 is a fragmentary view in perspective of the operating parts of the device shown in Figure 1.

Figure 4 is a view in elevation of the handle 45 of the device shown in Figure 1.

Figure 5 is a view in perspective of the work- 50 engaging pad of the device shown in Figure 1.

Figure 6 is a view in perspective of the weight used in applying pressure to the sanding device.

55 Figure 7 is a view in perspective of the frame and pad of the sander.

Figure 8 is a view in perspective of the motor for driving the mechanism of the sander, and

Figure 9 is a schematic diagram to illustrate 55 in exaggerated relation the motion which takes

place in a device constructed according to one embodiment of my invention.

Referring now to the drawings, a device constructed according to one embodiment of my invention includes a base 10, a sanding block 11, a motor 12, a linkage, indicated generally at 13, for driving the sanding block from the motor, a handle 14 for propelling and guiding the machine over the floor or other surface to be treated, and for furnishing a counter-acting lever arm or vibration damping means for the machine, and a weight 16 for applying pressure to the sanding block.

The base, shown more particularly in Figure 7, is roughly rectangular in shape and is provided 10 with a raised platform 10a at one end of the upper face thereof to act as a supporting means for the weight 16 and as a means for securing the pad 11 to the machine, as will hereinafter more particularly appear. The face 10a is provided with a 20 boss 10b threaded on the inner wall thereof as indicated at 10c. An intermediate portion of the base 10 is provided with oppositely-disposed, upwardly-projecting lugs 10d and 10e to which the arms of the handle 14 may be attached. The upper face of the base is also provided with a cylindrical cup shown at 10f for the reception of the motor 12.

The motor 12 is, of course, only one example 30 of a driving means, and any other suitable driving means might be employed. The motor is preferably adapted for operation in a vertical axis and electrical current is conducted to the motor by means of conductors indicated at 12a. The switch 12b on top of the motor is employed for 35 turning the current on and off. The shaft of the motor, indicated at 12c, is threaded, as indicated at 12d, in order that it may be threaded into the threaded hole 11a of the eccentric indicated generally at 17. The lock nut 12e is employed for 40 locking the shaft in place in the eccentric 17b. The shaft 12c extends below the lower face of the member 17e and an anti-friction bearing, such as the bearing 20, is mounted on the shaft. The eccentric bearing 20 is received in a cup 25 which 45 in turn is a part of a cross member 10i of base 10. The eccentric 17b thus acts as a cam, the bearings of which are provided by the cup 25, the bearing 20 and the bearings of the motor. In other words, the eccentric 17b acts as the cross 50 pin of a crank and the motor bearings and cup 25 act as the bearings for the crank shaft.

The motor here shown preferably rotates at approximately 1750 R. P. M., but of course motors with other operating speeds may be employed. 55

An anti-friction bearing is employed in conjunction with the eccentric 17b and the inner-race 17c is a wedge fit on the eccentric 17b, while the outer race 17d is received in a cup-like clamping member 17e, the clamping member being adapted to be tightly engaged to the outer race 17d by means of the ears 17f and locking screw 17g. The eccentric 17 is provided with a flange 17h on the opposite side of the cup-like member 17e and a wide strip of flexible material such as spring steel indicated at 18a is riveted, or otherwise secured to the under side of the flange 17h. The opposite end of the strip or link 18a is riveted to a flange 11a which is a part of the pad plate 11.

It is to be noted that the link 18a may be freely flexed in a direction vertical to the plane of rotation of the eccentric 17, but readily transmits turning and reciprocating motions from the eccentric to the sanding pad. The sanding pad may thus move freely up and down as pressure is applied to it without placing any bending moments on the eccentric to cause binding, injury, or wear on the eccentric.

25 The interior of the base 10 is hollow as indicated at 18 and the means for holding the sanding pad in place beneath the base includes the channel-shaped resilient members 19 and 21. These members may be of any suitable resilient material or any suitable shape.

A preferred means of securing the channel members 19 and 21 to the base 10 and to the pad plate 11 include the oppositely disposed plates 22 and 23. These plates are located within the box-like figure formed by the opposed channels 19 and 21, and they extend across the adjacent edges of the channels as illustrated. Screws 24 pass through the raised platform 10a and have threaded engagement with the upper plate 22 40 and when these screws are drawn tight the plate will securely grip the upper flanges of the resilient members 19 and 21. In the same manner screws 26 project through the bottom of the pad plate 11 and have threaded engagement with the lower plate 23, and when these screws are tightened the lower flanges of the resilient members 19 and 21 are tightly engaged to the pad plate 11. The edges of the pad plate 11 are turned up, as indicated at 11b, for assisting to confine the resilient members 19 and 21 and likewise these edges are provided with downwardly projecting flanges 11c adapted to be received in the grooves 27a of the pad 27 to hold the sheet of sand paper, or the like, indicated at 28, in place. The pad plate 11 is provided with upwardly projecting ears 11d and these ears have threaded bosses 11e 55 for the reception of set screws 29 adapted to hold the pad 27 in place on the pad plate 11.

The pad 27 is preferably provided with a layer 60 of resilient material, such as sponge rubber, as indicated at 31, on the lower face thereof. Of course any desired material such as emery cloth, sand paper, cotton cloth or the like may be substituted for the sand paper 28 in accordance with 65 the use to which the machine is to be put. It will be found that a pad of cloth, steel wool or like material may be placed on the floor beneath the pad 27 and, with no other fastening but the friction of the sand paper 28 on the material, the material will be moved by the pad to abrade or polish the floor as desired. This feature 70 makes it very easy to sand the floor and to then polish it without making any adjustment of the machine.

75 I have found it desirable, in using the ma-

chine, to employ a weight, such as indicated at 16, and this weight is recessed, as indicated at 16a, to fit closely around the motor 12 and circular flange 10f. It is preferably rounded, as indicated at 16b, for the sake of appearance. The 5 weight 16 is preferably provided with a combined carrying means and locking means illustrated at 32, and this locking means consists of the handle 32a which is received on a bolt 32b. The bolt 32b is threaded at its lower end, as indicated at 32c, and this threaded portion is received in a recess 16c extending from the lower face of the weight 16. A washer-like member 32d is provided on the lower end of the bolt above the thread 32c and within the recess 16c, so that 15 the handle 32a may be employed to carry the weight, the washer 32d acting to prevent the handle 32 from being withdrawn from the weight. The threads 32c of the bolt 32b may be threaded into the threaded boss 10b to lock the weight on 20 the base. It will be found that this weight serves two purposes, one in applying pressure to the sanding block 27 and also in minimizing vibration of the machine.

Vibration is, of course, present to a greater 25 or less degree in all reciprocating machines, and this condition is, of course, undesirable in a portable machine of this character. Although vibration might be substantially eliminated by adding sufficient weight to the machine, it is, of course, impractical to do this with a portable machine of the character of the present device. It has even been proposed to use oppositely reciprocating blocks to overcome vibration, but this entails superfluous and unnecessary mechanism. 35

The inertia of the weight 16 is effective to a limited degree to reduce vibration of the machine, but practical considerations make it undesirable to utilize this method of reducing vibration to a point where the machine is entirely 40 free or substantially free of undesirable vibration.

I have devised a unique means for further reducing and minimizing undesirable vibration of the machine as a whole. This is accomplished 45 by means of the handle 14. In order to secure a counter-balancing force reaction which will act against the direction of vibration of the base, I provide a locking means such as the turn-buckle 34 adapted to draw the side members 14a and 14b 50 of the handle 14 together to cause them to engage the weight 16 and motor 12 at the sides thereof to definitely lock the handle with respect to the base. It will be found that the handle 14 now acts as a counter-weight or counter-poise which, 55 apparently because of the long lever arm of the handle, sets up a counter-vibration which minimizes the vibration of the machine as a whole. I may carry this counter-action or damping effect to completion by applying an additional weight, 60 indicated at 36, to the upper end of the handle 14.

I preferably provide depending lug members 10g beneath the collar 10f and these lugs are drilled as indicated at 10h to receive a shaft 37 on which rollers or casters 38 are mounted. 65 These rollers permit the machine to be readily moved about by tilting downwardly on the handle 14 to raise the pad 27 from the floor.

In operation of a device constructed according to my invention, it will be found that the pad 27 70 will move not only with an oscillatory or reciprocatory movement but also with a circular movement, so that portions on the pad will move in the path of an ellipse, thus providing not only a reciprocatory movement of the pad, but also a 75

rotary motion, the combination of movements being particularly effective in the sanding and polishing operations for which the machine is intended. I have attempted to illustrate these movements in exaggerated relation in Figure 9.

As the eccentric 17b rotates, the pad plate 11 and pad 27 will be pushed from back to front and pulled from front to back. As the pad first starts to move from front to back, for instance, the eccentric is moving outwardly from the center line from the axis of rotation of the eccentric to the center of the pad and the entire pad will be rotated substantially about a vertical axis passing through the center of the pad (position A). As further outward and rotary movement of the eccentric occurs, the front to back movement of the pad begins, and as the eccentric further revolves through 180 degrees, the pad is pulled to the opposite side (position B) and is then rotated in the opposite direction on a vertical axis passing through the pad (position C). As rotation of the eccentric is continued through 360 degrees, the pad is moved in the opposite direction to complete the cycle of movement.

Although I have described a specific embodiment of my invention, it is apparent that modifications thereof may be made by those skilled in the art, without departing from the spirit and scope of my invention, as set forth in the appended claims.

I claim as my invention:

1. In a sanding machine, a base, an eccentric rotatably mounted with respect to the base, a pad resiliently mounted on the base by means of flexible channeled members and spaced from the eccentric, and a spring like link for connecting the pad with the eccentric flexible in a vertical direction to permit up and down movement of the pad with reference to the eccentric and stiff in the horizontal plane to transmit reciprocating movement from the eccentric to the pad.

2. In a sanding machine, a base, an eccentric rotatably mounted with respect to the base, means for driving the eccentric, a pad, resilient channeled member means for flexibly mounting the pad on the base, and a link for connecting the pad with the eccentric, the link being flexible in one direction only.

3. In a sanding machine, a base, a pad mounted for reciprocating movement with respect to the base, means for reciprocating the pad, means for damping the vibration of the base comprising a weight, and handle means for removably securing the weight to the base.

4. In a sanding machine, a base, a pad mounted for reciprocating movement with respect to the base, means for reciprocating the pad, means for damping the vibration of the base comprising a weight, and means for removably securing the weight to the base, the said means for securing the weight to the base including a carrying handle for engaging the weight to the base and for carrying the weight.

5. In a sanding machine, a base, a pad mounted for reciprocation with respect to the base, means for driving the pad with a reciprocating movement, and counter-poise means comprising a handle and a weight removably fixed to the base by the handle and extending above the base in a direction outside the plane of vibration of the base.

6. In a sanding machine, a base, a reciprocating mechanism mounted on the base for sanding a floor, and a counter-poise comprising a han-

dle and a weight in the handle extending above the base and removably secured to the base by means of the handle.

7. In a sanding machine, a base, reciprocating sanding means mounted on the base, means for damping the vibration of the base comprising a counter-poise including a weight extending above the base, and a handle extending therethrough to the base to removably fix the weight to the base and to carry the weight.

8. In a sanding machine, a substantially rectangular hollow base, resilient plate means engaged within the bottom of the base and extending therebelow, a pad mounted on the plate means, a motor mounted on the upper face of the base in spaced relation to the pad, a cross bar beneath the motor, an eccentric mounted for rotation in the cross bar and on the motor shaft, and a flexible link connecting the eccentric and the pad.

9. In a sanding machine, a base, resilient channel members mounted beneath the base and secured thereto, a sanding pad mounted on the lower edges of the channel members, an eccentric mounted in the base for rotation with respect thereto, a motor for driving the eccentric, a resilient link means connecting the eccentric and the pad, and a weight removably secured to the base by a handle.

10. In a sanding machine, a base, resilient channel members mounted beneath the base and secured thereto, a sanding pad mounted on the lower edges of the channel members, an eccentric mounted in the base for rotation with respect thereto, a motor for driving the eccentric, and a resilient link means connecting the eccentric and the pad, the resilient link being flexible in a vertical direction and stiff in the horizontal direction.

11. In a sanding machine, a base, a pad, resilient channel member means for mounting the pad on the base for twisting movement about a vertical axis and reciprocatory movement in a horizontal plane, a drive means for moving the pad including an eccentric mounted on the base for rotation in a horizontal plane, and a link flexible in a vertical plane but stiff in a horizontal plane whereby rotating movement of the eccentric is transferred by the link to the pad to cause twisting and reciprocating movement of the pad in a horizontal plane.

12. In a sanding machine, a base, a pad, resilient flexible channel members for mounting the pad on the base for twisting movement about a vertical axis and a reciprocatory movement in a horizontal plane and for limited vertical movement as a whole, a drive means for moving the pad including an eccentric mounted on the base for rotation in a horizontal plane, and a link flexible in a vertical plane but stiff in a horizontal plane whereby rotating movement of the eccentric is transferred by the link to cause twisting and reciprocating movement of the pad in a horizontal plane and to permit limited vertical movement of the pad to adjust its vertical position with reference to the base.

13. In a sanding machine, a base, a pair of resilient flexible channel members positioned with the edges of the flanges thereof adjacent each other and spaced from each other, a plate within the channel members and bearing against the under sides of the upper flanges, means for drawing the plate against the under side of the base to thus grip the upper flanges on the base, a sanding pad including a sanding pad plate on

the lower faces of the lower flanges, a plate on the upper faces of the lower flanges, means for drawing the plate down against the sanding pad plate, and means for applying twisting and reciprocating motion to the sanding pad.

14. In a sanding machine, a base, a flexible member beneath the base and a sanding pad on the lower face of the flexible member, said flexible member permitting both twisting and reciprocating movement of the pad, but preventing transverse movement of the pad, a shaft rotatably mounted in the base, an eccentric driven by the shaft, and a link, stiff in the horizontal

plane, connecting the eccentric and the sanding pad to cause the pad to move with both twisting and reciprocating movement.

15. In a sanding machine, a base, a pair of opposed channel members of resilient material having the edges of the flanges thereof adjacent to one another and spaced apart, a plate on the lower side of the upper flanges, and means for drawing the plate against the inner faces of the channel members to secure the channel members to the base.

RAYMOND A. REID.
